UNITED STATES PATENT OFFICE.

HARRY R. MASON, OF CHICAGO, ILLINOIS, ASSIGNOR TO THE WESTINGHOUSE AIR BRAKE COMPANY, OF PITTSBURG, PENNSYLVANIA, A CORPORATION OF PENNSYLVANIA.

VALVE MECHANISM.

SPECIFICATION forming part of Letters Patent No. 757,479, dated April 19, 1904.

Application filed August 18, 1901. Serial No. 72,245. (No model.)

To all whom it may concern:

Be it known that I, HARRY R. MASON, a citizen of the United States, residing at Chicago, in the county of Cook and State of Illinois, have invented certain new and useful Improvements in Valve Mechanism, (Case No. 5,) of which the following, taken in connection with the accompanying drawings, is a specification.

This invention has reference, primarily, to a pressure-reducing device comprising a casing in which there are mounted two valvular structures constructed to control the flow of fluid through passages in said casings and arranged to act in controlling such flow at different pressures. With said passages there are combined means for throwing the lower pressure structure out of action in order to insure the operation of the higher pressure structure. The valvular structure referred to is particularly designed for utilization as a feed device for an engineer's brake-valve in which the casing is provided with two pressure-reducing devices arranged to act at different pressures and with mechanism for throwing the lower pressure-reducing device out of action in order to insure the operation of the higher pressure-reducing device.

In order to more clearly bring out the character of my invention, I have shown the same as applied to an engineer's brake-valve used in connection with air-brakes, the structural features being shown in preferred form in the accompanying drawings, in which—

Figure 1 is a side elevation of an engineer's brake-valve with my improvement applied thereto. Fig. 2 is a view of the face of the main controlling-valve of the engineer's brake-valve. Fig. 3 is a view of the main-controlling-valve seat with my improvement applied at the side of the casing. Fig. 4 is a vertical section taken substantially on the line 4-4, Fig. 3, and showing the main portions of the engineer's brake-valve to which my improvement is applied. Fig. 5 is a transverse vertical section through the engineer's valve, the left-hand half being shown substantially on the line 5-5 and the right-hand half on the

line 5'-5' of Fig. 4. Fig. 6 is still another transverse vertical section taken substantially on line 6-6 of Fig. 3 and showing some of the details of my improvement. Fig. 7 is a section on the line 7-7 of Fig. 6; and Fig. 8 is a section on a somewhat larger scale, showing some of the passages in diagrammatic form, so as to more clearly illustrate the features of my invention.

Save in so far as concerns the improvement relating to my invention the brake-valve shown in the accompanying drawings is of well-known construction, comprising a main body or casing 9, having a connection 10 from a main reservoir and another connection 11 leading to a train-pipe, a main governing or regulating valve 12, operating upon a seat 13 in the casing 9 and inclosed in a chamber formed by a cap 14 and controlling divers ports and passages in the valve-seat, among which is one, 15, known as a "feed-passage," which is that passage through which air in the running position of the valve flows from the main reservoir to the train-pipe, which is at all times in open communication with the cavity 16. The connection from the main reservoir is in open communication with the chamber which surrounds the valve 12, and air passes from thence through an opening 17 and a passage 18 into another passage 20, formed in a casing 21, in which my improved mechanism is mounted.

Referring now more particularly to Fig. 8, which shows my invention a little more clearly, because the arrangement of the passages has been somewhat altered to bring out more clearly their relation to each other on a single view, it will be seen that the passage 20 has two branches leading to the ports 21 and 22, which are controlled, respectively, by valves 23 and 24, held shut by the springs 25 and 26, confined in the caps 27 and 28, as shown. The chamber 29 surrounding the valve 23 is in direct communication with the outlet-passage 30, which leads ultimately to the train-pipe through the passage 31 and the passage 15, before referred to, by means of the cavity 32 in the under face of the slide-valve 12. The

chamber 33, which surrounds the valve 24, leads downward through a passage 34, controlled by the stop-cock 35, having a handle 36 capable of ready manipulation from the exterior of the casing, and when the cock 35 is open the passage 34 is in open communication, as shown in Fig. 8, with the passage 30 and also from said passage to the train-pipe, as before described.

10 The purpose of my invention, as shown in the accompanying drawings, will now be more clear in connection with my description of the operation of the mechanism referred to, which is as follows: Assuming the parts to be in the 15 position shown in the several views of the drawings, with the cock 35 open, as shown in Fig. 8, air from the main reservoir will pass through the port 17, passage 18, and passage 20 to the under face of the valves 21 and 22, 20 and the valve 24 being set to open at a lower pressure, because of the spring 26 above the same being weaker than the spring 25 above the valve 23, the valve 24 will open and permit air to flow past and down through the passage 34 25 and the cock 35 into the train-pipe by means of the communication established from the passage 30 through the passages 31 15 and the cavity in the slide-valve 32. Assuming that the strength of the spring 26 is such as to hold 30 the valve 24 down with a pressure of, say, ten pounds to the square inch, it is obvious that to maintain a pressure of ninety pounds in the train-pipe it will be necessary for the main-drum pressure to increase to one hundred pounds before the valve 24 will open and feed the train-pipe from the main reservoir. If now it be desired to carry a lower pressure in the train-pipe—say seventy pounds—with ninety pounds in the main reservoir, as 35 suming the spring 25 to be set to hold a pressure of twenty pounds on the valve 23, the desired result can be accomplished by closing the valve 35, when the low-pressure valve 24, having the ten-pound spring, although it 40 opens, will not permit the air to reach the train-pipe on account of the closure of the valve 35, and then the pressure will have to be increased in the main reservoir to twenty

50 pounds above the train-pipe pressure—that is, to ninety pounds—before the valve 23 will open and permit air to flow past into the train-pipe. Thus by the mechanism shown I am enabled to determine the operation of the reducing device at any point or at any pressure desired.

55 Having thus described my invention, what I claim as new, and desire to secure by Letters Patent, is—

1. A feed device for an engineer's brake-valve, comprising a casing, two pressure devices in said casing, arranged to act at different pressures, and a separate valve for throwing the lower pressure device out of action, in order to insure the operation of the higher pressure device, substantially as described. 60

2. A pressure device, comprising a casing, two valvular structures therein for controlling the flow of fluid therethrough, arranged to act at different pressures, and an independent valve for throwing the lower pressure structure 70 out of action, in order to insure the operation of the higher pressure structure, substantially as described.

3. The combination with an engineer's brake-valve of a feed device comprising a casing containing two valves controlling communication between the main reservoir and train-pipe, the valves being set to open at different pressures, and means independent of the engineer's valve for cutting the low-pressure 75 valve out of operation.

4. The combination with an engineer's brake-valve of a feed device comprising a casing containing two spring-actuated valves for controlling communication between the main 80 reservoir and train-pipe, the springs being adjusted for different pressures, and an independent valve for cutting the low-pressure feed-valve out of operation.

90 In witness whereof I have hereunto set my hand in the presence of two subscribing witnesses.

HARRY R. MASON.

In presence of—

PAUL CARPENTER,
H. W. SMALLEY.
